ELECTRIC SWITCHES

George Alfred Gayler, Bletchley, England, assignor to
Wipac Development Limited, Bletchley, England

Application May 16, 1955, Serial No. 508,680

Claims priority, application Great Britain June 3, 1954

5 Claims. (Cl. 200—16)

The present invention relates to electric switches of the three-pole one-way type, that is to say of the type having three terminals which in the "off" position are insulated from one another and in the "on" position are all connected together. Such switches may be required, for example, as will be explained later, as stop switches operated by the brake pedal of a road vehicle to illuminate two spaced stop lights when it is required that the stop lights should also be used as turn indicating lights.

According to the present invention a three-pole, one-way electric switch comprises two members which are movable relatively to one another in a first direction when the switch is changed from its "on" to its "off" position and vice versa, one of the members carrying three mutually-insulated yielding contacts and the other member carrying a contact piece mounted in such a manner as to be capable of limited movements relatively to the said other member in a plane at right angles to the said first direction, the arrangement being such that when the switch is adjusted to its "on" position the contact piece is free to slide in the said plane to take up a position of equilibrium in contact with the three yielding contacts thereby enabling very good electric contact to be obtained between the contact piece and the three yielding contacts. The contact piece may be constrained against rotary movement in the said plane: for example it may be provided with three flats adapted to engage the three yielding contacts, respectively, in the "on" position and suitable shaped portions on the first-named member in the "off" position.

In a preferred construction the contact piece has an approximately hexagonal outer contour and is in the form of a flat annulus mounted between two insulating members which act as guides for the contact piece and permit movement thereof in the said plane.

The invention will be described, by way of example, with reference to the drawings accompanying the specification in which

Fig. 1 is a view in longitudinal section of a stop switch according to the invention,

Fig. 2 is a view in end elevation from the right in Fig. 1 with the cover and sealing washer removed,

Fig. 3 is a view in end elevation from the left in Fig. 1, and

Fig. 4 is a circuit diagram showing how the switch of Figs. 1 to 3 may be used as a stop switch operated by a brake pedal.

Referring to Figs. 1 to 3, the fixed member of the switch comprises a mounting plate 10 carrying a hollow insulating body portion 11. Within a hexagonal space in the body 11 are three yielding contacts 12 connected to three terminal pieces 13, respectively, as shown in the case of one terminal piece in Fig. 1. The movable member comprises a rod 14 having a head 15. A contact piece 16

2

having a hexagonal outer contour is mounted between two insulating washers 17 and 18 and the parts 16, 17 and 18 are pressed by a spring 19 against the head 15 acting as an abutment. The spring 19 bears against a washer 20 which abuts against a sealing washer 21, for example of felt, on the inside of a cover 22 which is secured on the insulating body portion 11 by three tongues 23 cut out of the cover and engaging in suitable notches formed in the body portion 11.

5 Connections are made with the terminal pieces 13 by screws 24 and the terminal pieces are provided with insulating covers 25.

The rod 14 may be coupled to the brake pedal through a spring 26. The rod 14 is free to rotate relatively to the contact piece 16 and body portion 11.

In Fig. 4 the switch of Figs. 1 to 3 is shown at 27. It is arranged, when in the "on" position, to close a circuit between a battery 28 and two spaced red lamps 29 on a motor cycle or motor car. When a turn indicator switch 30 is set to the right or left, a circuit is closed from the battery 28 and the appropriate one of the lamps 29 through a thermo cut-out switch 31, of well-known type, whereby the lamp that is operative is caused to flash.

I claim:

25 1. A three-pole one-way electric switch comprising two members which are movable relatively to one another in a first direction when the switch is changed from its "on" to its "off" position and vice versa, three mutually-insulated yielding contacts mounted on one of said members, 30 a contact piece capable of substantial but limited movements at right angles to said first direction to assure good electric contact between said three mutually-insulated yielding contacts and said contact piece, and guide means having two guide surfaces facing one another and in planes substantially at right angles to said first direction, said surfaces being in guiding engagement with said contact piece.

2. An electric switch according to claim 1, comprising means constraining said contact piece against rotary 40 movement about said first direction.

3. An electric switch according to claim 1, wherein said contact piece is provided with three flats positioned to engage the three yielding contacts, respectively, in the "on" position and to engage suitably shaped portions on the first-named member in the "off" position.

4. A three-pole one-way electric switch comprising two members which are movable relative to one another in a first direction when said switch is changed from "on" to "off" position and in an opposite direction when said switch is changed from "off" to "on" position, three mutually-insulated yielding contacts mounted on one of said members, a contact piece capable of substantial but limited movements at right angles to said first direction to assure good electrical contact between said three mutually-insulated yielding contacts and said contact piece, and guide means consisting of two insulating members having guide surfaces facing one another and in planes substantially at right angles to said first direction, said surfaces being in guiding engagement with said contact piece, said contact piece having an approximately hexagonal outer contour and being in the form of a flat annulus mounted between said two insulating members which act as guides for said contact piece and permit movement thereof in said planes.

5. A three-pole one-way switch comprising a hollow body portion, three yielding contacts mounted in the interior of said body portion, extending in a first direction,

and having portions more closely spaced than the remainder thereof, an actuating member slideable in said direction between said contacts, supporting means mounted on said actuating member and having a pair of annular faces in planes perpendicular to said direction, and a contact-making annulus mounted between and in engagement with said annular faces and capable of limited movement parallel to said planes to assure good electric contact between said three yielding contacts and said contact-making annulus.
